UNITED STATES PATENT OFFICE.

ARCHIE FEINBERG, OF CHICAGO, ILLINOIS, AND ISADORE M. HALVERSON, OF BOONE, IOWA, ASSIGNEES TO ARCTIC NU-AIR CORPORATION, OF CHICAGO, ILLINOIS, A CORPORATION OF ILLINOIS.

ROTOR FOR BLOWERS.

Application filed May 24, 1926. Serial No. 111,091.

This invention relates to improvements in rotors, fans or impellers for blowers and it consists of the matters hereinafter described and more particularly pointed out in the appended claims.

One of the objects of the present invention is to provide an improved rotor, fan or impeller for blowers which is simple in construction and which though light in weight is strong and rigid enough to amply withstand the strains imposed upon it in use.

A further object of the invention is to provide a rotor, fan or impeller which may be readily taken apart for passage through narrow doorways and then readily and quickly reassembled.

The above mentioned objects as well as others, together with the many advantages thereof will more fully appear as we proceed with our specification.

In the drawings:—

Fig. 1 is a perspective view of a rotor, fan or impeller embodying our invention.

Fig. 2 is a fragmentary view in end elevation of the same on an enlarged scale.

Fig. 3 is a fragmentary view on an enlarged scale of a portion of one of the end rings as looked at from the inside thereof and showing some of the vanes in transverse vertical section.

Fig. 4 is a transverse vertical detail sectional view as taken on the line 4—4 of Fig. 3.

Fig. 5 is a detail vertical sectional view as taken on the line 5—5 of Fig. 3.

Fig. 6 is a longitudinal sectional view through the rotor as taken on the line 6—6 of Fig. 2.

Fig. 7 is a detail vertical sectional view as taken on the line 7—7 of Fig. 2.

Figs. 8 and 9 are perspective views of parts embodied in our improved rotor, fan or impeller and which will be more fully referred to later.

In general our improved rotor includes a shaft and two annular end plates or rings made up of segments fixed to the shaft by radial spokes or arms, said rings being connected together by vanes disposed parallel to the shaft.

Referring now in detail to that embodiment of the invention illustrated in the accompanying drawings, 1 indicates the shaft

of the rotor and concentric therewith are two longitudinally spaced annular end plates or rings 2—2 connected together by the vanes or blades 3—3. Each end plate or ring 2 is made up of a plurality of segments 4 and as shown herein there are four of such segments embodied in each ring. Each segment which is made of sheet metal of a shallow channel shape cross section, includes a radial plate or ring body 4^a and inner and outer annular flanges 4^b and 4^c respectively. Rigidly fixed to one end of the body of each segment, on the outer surface thereof as by means of the rivets 5^a is a connector plate 5, which also includes inner and outer flanges 5^b and 5^c respectively to engage the respective flanges of the associated segment 4. Such a connector plate is best shown in perspective in Fig. 8. When all the segments making up a complete ring are in end to end engagement, the free end of one connector plate 5 overhangs the other end of an abutting segment 4 and is detachably secured thereto by bolts and nuts 6, locking plates 7 being employed in connection with said bolts to prevent the possibility of their becoming loose.

Associated with each end plate or ring is a plurality of spokes or radial arms 8 for supporting the rings in operative relation with respect to the shaft 1. Each spoke or arm is made of a channel with its flanges 8^a disposed outwardly and portions of the ends of said flanges at the outer end of each spoke or arm are cut away so that shoulders 8^b are thus provided. Said shoulders are engaged with the inner flange 4^b of the associated segment, and the web 8^c of the spoke or arm beyond said shoulders is engaged with the inner face of the segment and secured thereto by bolts and nuts 9 which are held against rotation by locking plates 10 as best shown in Fig. 7, said plates being similar to the plates 7 before mentioned. The inner end of all of the spokes of each end ring, which spokes are disposed radially with respect to the shaft 1 are bolted to the outer face of an associated collar 11 one of which in turn is fixed to the shaft 1 a suitable distance from each end thereof.

As before stated, the two rings 2—2 are connected together by a plurality of vanes or blades 3—3 and as shown herein there are five of said vanes or blades associated with

each pair of segments 4 of the respective rings. Each blade which is disposed with its edges radial to the shaft 1 comprises an elongated sheet metal strip or plate, the margins of which are turned over upon one surface of the vane to provide stiffening flanges 3^a and intermediate said flanges the vane is provided on one side with an upset V shaped rib 3^b defining a groove or channel on the other side of vane as best shown in Fig. 3. Each end of each vane is bent at a right angle to provide an ear 3^c which is engaged with the inner surface of the body 4^a of a segment 4. Associated with the ends of each vane or blade is a duplex reinforcing clip 12 best shown in perspective in Fig. 9. Said clip comprises two spaced angle bar portions each including horizontal and vertical flanges 12^a—12^b and connecting the two horizontal flanges thereof is an angular bridge portion 12^c. When said clips are in place, the horizontal flanges engage the underside of the ends of each vane and are secured thereto as by the rivets 13 while the vertical flanges 12^b are engaged against the ears 3^c and rivets 14 pass through the segment body 4^a, ears 3^c and flanges 12^b to secure said parts together, the angular bridge portion 12^c engaging the end portion of the V shaped rib 3^b all as best shown in Figs. 3 and 5. The clips reinforce the vanes at their ends and prevent fracturing of the same at the junctions or corners of the vane and ears thereof.

To assist the vanes in securing the rings together so as to reduce the strain on said vanes, we may employ long tie bolts 15, one of which is disposed in the groove defined by the rib 3^b in one of the vanes of each set associated with a pair of segments 4. Each bolt has a nut 15^a by which the same may be tightened and to prevent whipping of the mid portion of the bolt out of the groove we employ inverted U shaped clips 16 straddling the groove in said vane as best shown in Fig. 6.

By removing the bolts 6 and 9 it is apparent that the rotor may be disassembled for passage through narrow doorways, which are often met with in making installations in buildings already erected, and may thereafter, as easily again be reassembled. It is strong and rigid and is so reinforced and strengthened as to amply withstand operating pressures.

While in describing our improved rotor, we have referred to many details of construction as well as form and arrangement

of the parts thereof, the same is by way of illustration only so that we do not wish to be limited thereto except as may be pointed out in the appended claims.

We claim as our invention:

1. A rotor for a blower embodying therein a shaft, end rings concentric with said shaft and each comprising a plurality of segments, blades interposed between and fixed at their ends to said end rings, each segment carrying a part on one end adapted to overhang the end of an abutting segment, means for detachably securing said overhanging part to said end of the abutting segment, and spokes connecting the end rings to said shaft.

2. A rotor for a blower embodying therein a shaft, end rings concentric with said shaft and each comprising a plurality of segments, blades interposed between and fixed at their ends to said end rings, means for detachably connecting the ends of the segments of each ring together, and spokes connected at one end to the shaft and detachably connected at the other end to an associated ring segment between two adjacent blades.

3. A rotor for a blower embodying therein, an end ring, a shaft, spokes fixed at their inner ends to said shaft, said spokes each having a shoulder near the outer ends to engage the inner periphery of the ring and means for securing the outer ends of said spokes to the ring.

4. A rotor for a blower embodying therein, an end ring of channel cross section and including inner and outer annular flanges, a shaft, spokes fixed at one end to said shaft and having parts cut away at their outer ends to form shoulders to engage the inner flange of the ring and means for detachably connecting the outer ends of said spokes to said ring.

5. A rotor for a blower embodying therein, an end ring of channel cross section and including inner and outer annular flanges, a shaft, spokes, each spoke being of a channel cross section and fixed at its inner end to said shaft and having portions of the sides thereof at the outer ends cut away to form shoulders to engage the inner flange of the ring and means for detachably connecting the outer ends of said spokes to the ring.

In testimony whereof, I have hereunto set my hand this 27th day of April, 1926.

ARCHIE FEINBERG.

In testimony whereof, I have hereunto set my hand this 18th day of May, 1926:

ISADORE M. HALVERSON.
